UNITED STATES PATENT OFFICE

JESSE C. MARTIN, JR., OF LOS ANGELES, CALIFORNIA

FLANGE AND CONNECTION FOR TUBULAR HEATING ELEMENTS

Application filed June 24, 1931. Serial No. 546,647.

The hereinafter described invention relates primarily to the attachment of tubular water heating elements as positioned between the firebox sheets of a locomotive boiler for the purpose of circulating water and generating steam, although its application may well be extended to the plated surfaces of other types of boilers and pressure holding vessels for establishing fluid communication between the respective surfaces thereof.

My invention contemplates among its objects the formation of flanges on the ends of tubular heated water carrying elements for attachment to the sheets of a locomotive firebox in such manner that the metal walls of the tube adjacent its end will not be subjected to the amount of heating and working as at present required to form the flange integral with the tube and which unduly upsets the metal structure, reduces its resistant qualities, and causes subsequent failure in service in assimilating the stresses set up by the heat of combustion in the firebox of the locomotive boiler by providing a flange which in its construction will require only a comparatively slight deformation of the metal at the tube and without impairing its original metal characteristics and sustaining ability, and which is distinguished from a flange formed with a full or continuous face by having a plurality of faces with a separation therebetween so established to relieve the stretching of the metal now required on the formation of a full face flange, the separation so formed being filled with the metal of the firebox sheet while the abutting edges of the sheet and flanges are welded together and the flange faces staybolted in accordance with State and Federal rules and regulations.

One of the objects of my invention is to make a connection for the ends of tubular elements as attached by welding and staybolted to the sheets of locomotive fireboxes so that a greater portion of the firebox sheets will function in forming the juncture of the elements to the sheets than at present, that is, to make the opening formed in the firebox sheet to receive the flange so that a part of the surface around the opening will be utilized as a means of assisting me in providing a

flange with a divided face or a split flange, so to speak, which will not so excessively work the metal of the tubular end in its formation and which will give to the tubular elements through the increased efficiency of their flanged terminal connections greater life and lower maintenance cost in service in satisfying the strains of expansion and contraction encountered.

Another object of my invention is to split a tubular member at its ends and then to turn back the metal between the splits in such manner as to form an attaching flange, thereby avoiding unduly heating and drawing the metal at the tube end as when a full flange is formed or drawn thereon, and furthermore in applying the flange of my invention so formed to utilize a part of the metal of the firebox sheet to which the edges of my flange are welded to fill the spaces between the splits, thereby retaining the character of the metal structure of the tube at its connecting ends and effectually preventing cracking and failure of the tubular elements at these vital points when subjected to the heat of combustion.

A further object of my invention is to provide flanges on the ends of tubular heated elements such as used in the fireboxes of locomotive boilers which can be formed at a lesser cost than the flanges as now fashioned on such elements and which will reduce the cost of terminally connecting the elements to the firebox sheets, in fact to provide a flange connecting structure which will through its new and novel conformation permit the use of a materially smaller size of flange for the purpose intended than that at present employed, thereby saving the cost of staybolt removal now required in making the opening in the staybolted area of the firebox sheets for the reception of the present flange and the subsequent cost of re-staybolting the increased area of same over the flange of my structure.

In order that my invention may be fully understood by those skilled in the art, reference is made to the illustrative embodiments set out on the accompanying drawings, in which,

Fig. 1 is a sectional elevation of the fire-

box of a locomotive boiler showing tubular elements having flanges as formed and joined to the side sheets and crown sheets of the firebox in accordance with the improvements of my invention.

Fig. 2 is a half sectional end elevation taken on line 2—2, Fig. 1, looking toward the door sheet of the firebox, while Fig. 3 is a half sectional end elevation taken on line 3—3, Fig. 1, looking toward the flue sheet of the firebox.

Fig. 4 shows a portion of the firebox sheet and the shape of the opening as initially cut in the sheet to receive the flanged end of my construction, the opening being prepared to receive the flanged end as formed on an elongated tube.

Fig. 5 shows the opening of Fig. 4 after the metal of the sheet as utilized for filling in the spaces as formed at the turned-over ends of my flanges are trimmed and bent up to fill respective spaces as formed at the end of the tube by my improved flange.

Fig. 6 is a sectional view taken on line 6—6, Fig. 5, while Fig. 7 is a sectional view taken on line 7—7, Fig. 5, both views being taken to further show the bent-up ends of the plate which are to fill in at the ends of my flange.

Fig. 8 is a plan view of improved flange as formed on an elongated tube of size adapted to fit the trimmed opening in the firebox sheet as shown by Fig. 5, the elongated tube being shown in section.

Fig. 9 is an end elevation of the tube and flange of Fig. 8 showing the depression at the end of the tube as formed in making my improved flange and which depressions are filled in by the bent-up ends of the firebox sheet as shown in Figs. 5, 6 and 7.

Fig. 10 is a broken perspective view of my improved flange as formed on an elongated tube, the tube being butt welded in position in the opening as prepared in the firebox sheet to receive it and staybolted through the flat sides of the flange to accord with the stipulated practices of State and Federal authorities.

Fig. 11 illustrates another form of my invention adapted to suit a tube of circular cross-section. The view shows the opening as initially cut in the firebox sheet, a portion of which is shown.

Fig. 12 shows the opening of Fig. 11 as trimmed to receive my flanged end, the inner points of the opening being shaped and bent outwardly to accord with the depressions as made at the end of the tube during the formation of my improved flange thereon.

Fig. 13 is a sectional elevation taken on line 13—13, Fig. 12, to show clearly how the inner points of the opening of Fig. 12 are bent outwardly.

Fig. 14 is a plan view of my flange as formed on the circular tube of size to fit the

opening in the firebox sheet as shown in Fig. 12, the tube being in section.

Fig. 15 is a side elevation of a portion of the circular tube end of Fig. 14 with my improved flange as formed thereon.

Fig. 16 is a perspective view of the end of a tube of circular cross-section showing how the spaces between the turned-over ends of the tube as made in the formation of my flange have been filled in by the outwardly bent portions of the firebox sheet in the opening made therein, the edges of the firebox sheet and the edges of the flange being butt welded together and the faces of my flange being staybolted in accordance with Federal and State requirements.

Fig. 17 is also a perspective view showing the end of a tube of circular cross-section formed with a single depression in its flanged face, the firebox sheet being bent to fit the depression and the edges of the flange and firebox sheet being butt welded in fluid tight engagement.

In the drawings Figs. 1 to 10 inclusive, which show the elongated tube form of my invention, numeral 10 denotes the elongated tube itself upon the ends of which are fashioned the new and novel flanges of my invention with divided face portions 11 and 12 and depressed portions or separations between the flange faces as denoted at 13 and 14. As shown in the view of Fig. 4, I initially cut an opening in the firebox sheet, the contour of which is denoted by numeral 15, so as to receive the divided flange portions 11 and 12, and the depressed portions 13 and 14, the portions of the firebox sheet around the opening 15 which I utilize to fit the depressed portions 13 and 14 being denoted by numerals 16 and 17 respectively. Numerals 16a and 17a of Figs. 5, 6 and 7 show how the portions 16 and 17 around the opening 15 are trimmed and bent outwardly to fit the depressed separations 13 and 14 between the flange faces 11 and 12, the edges of the flange faces and depressed separations all being arranged for butt welding to the respective edges of the opening 15 to which they have been fitted for this purpose and the flange faces 11 and 12 being staybolted as denoted at 18. This work of welding and staybolting is carried out in conformity with the existing rules and regulations prescribed by State and Federal authorities.

In the formation of my improved flange and as descriptive of at least one way in which I now form it, I split, the end of the tubular element 10, preferably longitudinally therewith, and so as to make the flange faces 11 and 12 when turned over symmetrical and in as many places as desired to suit the particular cross-section of the tubular element employed, for example, the elongated tube 10 of Figs. 1 to 10 is split in two places opposite each other while the circular tube of

Figs. 11 to 16 is cut in four places diametrical-
ly opposite from each other. These splits
at the tube ends may be made in any prac-
tical manner best suited to working the metal
5 of the tube, my purpose being to provide a
separation between flange faces 11 and 12 in
the least expensive manner so that I may be
enabled to turn over the ends of the tube to
form the flange faces 11 and 12 with a mini-
10 mum of heating and forming, which it is one
of the most important features and advan-
tages of my invention to effect in saving the
metal ends from distortion through exces-
sive drawing which now causes their failure
15 in service.

In the illustrative showing of my invention
Figs. 1 to 10 inclusive, I have shown its
application to a welded and staybolted elong-
ated tubular element made of plate of like
20 character as the plate to which it is attached,
and in Figs. 11 to 16 inclusive as applied to
a continuous walled tube or element of cir-
cular cross-section so as to bring out its prin-
ciples under different conditions of tubular
25 construction.

In Figs. 11 to 16 inclusive the tubular ele-
ment of circular cross-section is denoted by
numeral 10a, and the same has been split at
its end four times into substantially equal
30 sections and the sections between the splits
turned over to form four like and symmetri-
cally arranged flange faces 20, 21, 22 and 23
and depressions 24, 25, 26 and 27 between
the flange faces.

35 In similar manner as heretofore described
and as shown in Fig. 11, the firebox sheet is
initially prepared with my particularly con-
toured opening 28 having points 29, 30, 31
and 32, which points as shown in Figs. 12
40 and 13 are prepared by fitting and bending
outwardly as shown at 29a, 30a, 31a and 32a
so that they fill the depressions 24, 25, 26 and
27 respectively in such manner as to be butt
45 welded and the flange faces 20, 21, 22 and 23
staybolted as shown by numeral 18 to meet the
established State and Federal rules and regu-
lations for welding and staybolting in the
area of the firebox sheets.

In Fig. 17 a circular cross-section tubular
50 element 10b has been split in a single place
and the metal of the element end turned over
to form a flange 20b with a single depres-
sion 24b, the metal of the firebox sheet be-
ing bent as shown at 29b so as to fill the de-
55 pression 24b and the edges of the flange and
firebox sheet joined together by welding.

However, in certain applications of my in-
vention to the lower fluid pressure services
it may not be necessary in meeting the safety
60 rules and regulations as set out to staybolt
the flanged portions as shown in the illustra-
tive views herewith, in which case the strength
of the weld is relied upon in making the junc-
ture.

65 In the application of my invention to the

elongated shape of tubular element 10, I am
enabled to afford a special feature and advan-
tage in that the opening 15 as cut in the fire-
box sheet is much smaller than an opening
which would be required to accommodate a
flange made with a full or uninterrupted face
70 because I eliminate the end flange faces on the
tube and provide only the side flange faces
11 and 12 between the depressions 13 and 14.
This effects a very substantial and desirable
constructional feature and advantage through
75 avoidance of cutting out a great many stay-
bolts on either end of the opening as when
the full flange with end faces is employed
and the final replacement of these staybolts
80 through the face of the flange is required to
be made in accordance with the established
rules and regulations.

85 My purpose may be said to be to provide the
smallest amount of flange face possible in
meeting the requirements of safety so as to
avoid the expensive cost of removing and re-
placing staybolts.

Numerous modifications for carrying out
the principles of my invention will make
themselves manifest to those skilled in the art,
and I therefore do not wish to restrict myself
to the exact showing herewith made, the
scope of my invention being limited only to
the extent of the claims as appended.

95 I claim:

1. A connection for joining a tubular heat-
ed element to the sheet of a firebox comprising
a split flange on the end of the element, and
the firebox sheet having an opening with a
100 contour shaped to fit said flange and split
portion, the edges of said flange and split
portion butt welded to the edges of said
opening.

2. A connection for joining a tubular heat-
ed element to a sheet of a firebox comprising a
flange with a split in its face and a depression
formed thereby inward from its periphery,
an opening in the firebox sheet, its edge embrac-
105 ing a portion of the flange and fitting the
edges of said depression and a butt weld unit-
ing said edges.

3. A connection for joining a tubular
heated element to the staybolted sheet of a
firebox comprising a flange with a split in
115 its face and a depression formed thereby in-
ward from its periphery, an opening in the
firebox sheet embracing a portion of said pe-
riphery and fitting the edges of said depres-
sion, a butt weld uniting said edges, and stay
bolts for joining said flange in like manner
as the sheets in the firebox.

120 4. The method of forming a connection be-
tween a tubular element and a plated sur-
face which consists in splitting the end of the
element and turning back the metal thereof to
form a flange having a separation in its face,
making an opening in the plated surface to
receive the edges of the flange and separation,

and bonding said edges to the edges of the opening by welding.

5. The method of forming a connection between a tubular heated element and the sheet 5 of a firebox which consists in splitting the end of the element into sections, turning over the sections to form flange faces on the end thereof, making an opening to utilize portions of the firebox sheet residing in the opening as cut, to receive the edges of said flange and to fit the edges of said separations, and bonding the respective edges together by welding.

10 6. The method of connecting a tubular member to a plate which comprises, forming 15 a substantially longitudinal slit in the end of the member, bending the material at each side of the slit outwardly to produce a flange divided by a recess defined by the edges of 20 said slit, forming an opening in the plate contoured to receive the edge of said flange and recess and butt welding the edges of said opening, flange and recess.

25 7. The method of connecting a tubular member to a plate which comprises forming a substantially longitudinal slit in the end of the member, bending the material at each side of the slit outwardly to produce a flange portion at each side of the slit, the edges of 30 said portions joining in a recess defined by the edges of said slit, said edges in said recess curving from the plane of the face of the flange to merge into the surface of said member, forming an opening in the plate contoured to receive the edges of said flange and 35 recess including a portion projecting into the opening to fill said recess in butt-welding relation, deflecting said projecting portion to agree with the curve of the recess edges, and 40 butt welding the edges of said flange portions and recess to the edges of said opening and projecting portion.

In testimony whereof, I have hereunto set my hand at Los Angeles, California, this 20th 45 day of June, 1931.

JESSE C. MARTIN, JR.
